(57) **CLAIM**

The ornamental design for an octagonal shelving pole, as shown and described.

DESCRIPTION

FIG. 1 is a top perspective view of an octagonal shelving pole;

FIG. 2 is a front elevational view thereof;

FIG. 3 is a top plan view thereof; and,

FIG. 4 is a bottom plan view thereof.

A rear elevational view is not shown because it is a mirror image to the front elevational view shown in FIG. 2. A right-side elevational view is not shown because it is a mirror image to the front elevational view shown in FIG. 2. A left-side elevational view is not shown because it is a mirror image to the front elevational view shown in FIG. 2. The broken lines depict portions of the article that form no part of the claimed design. The octagonal shelving pole is shown with a symbolic break in its length. The appearance of any portion of the article between the break lines forms no part of the claimed design.
